US00D889415S

(12) **United States Design Patent** (10) Patent No.: **US D889,415 S**
(45) Date of Patent: ** Jul. 7, 2020

(54) **PROCESS CARTRIDGE FOR IMAGE FORMING APPARATUS**

(71) Applicant: **CANON KABUSHIKI KAISHA**,
Tokyo (JP)

(72) Inventors: **Toru Oguma**, Shizuoka-ken (JP);
Naoya Asanuma, Shizuoka-ken (JP);
Tetsuya Numata, Shizuoka-ken (JP);
Takuya Kawakami, Shizuoka-ken (JP);
Yohei Kusano, Shizuoka-ken (JP);
Daisuke Hiramatsu, Tokyo (JP);
Takayuki Yada, Shizuoka-ken (JP);
Takatoshi Hamada, Shizuoka-ken (JP);
Go Torii, Shizuoka-ken (JP); **Hiroaki Noshō**, Shizuoka-ken (JP)

(73) Assignee: **Canon Kabushiki Kaisha**, Tokyo (JP)

(**) Term: **15 Years**

(21) Appl. No.: **29/672,793**

(22) Filed: **Dec. 10, 2018**

Related U.S. Application Data

(62) Division of application No. 35/503,667, filed on Apr. 26, 2017 (U.S. filing date under 35 U.S.C. 384), and having an international filing date of Apr. 26, 2017, now abandoned.

(57) **CLAIM**

The ornamental design for a process cartridge for image forming apparatus, as shown and described.

DESCRIPTION

FIG. 1 is a front view of the process cartridge for image forming apparatus, showing our new design;

FIG. 2 : Is a back view thereof;

FIG. 3 : Is a top plan view thereof;

FIG. 4 : Is a bottom plan view thereof;

FIG. 5 : Is a left side view thereof;

FIG. 6 : Is a right side view thereof; and

FIG. 7 : Is a perspective view thereof; and,

FIG. 8 is another perspective view thereof.

1 Claim, 8 Drawing Sheets
